UNITED STATES PATENT OFFICE.

WILLIAM F. CUMMINGS, OF BRADFORD, VERMONT.

AUTOMATIC CAR-BRAKE.

SPECIFICATION forming part of Letters Patent No. 358,547, dated March 1, 1887.

Application filed January 13, 1887. Serial No. 224,230. (No model.)

To all whom it may concern:

Be it known that I, WILLIAM F. CUMMINGS, a citizen of the United States, residing at Bradford, in the county of Orange and State of Vermont, have invented certain new and useful Improvements in Automatic Car-Brakes; and I hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to automatic car-brakes; and it consists in the novel construction and combination of the parts, hereinafter fully described and claimed.

In the drawings, Figure 1 is a plan view, 20 from above, of portions of a car-truck provided with a brake according to this invention. Fig. 2 is a longitudinal vertical section taken on the line $\alpha\alpha$ in Fig. 1.

A is the lower part of a car-frame, provided 25 with axle-boxes of ordinary construction.

B are the car-wheels, secured upon axles b , journaled in the said boxes.

C is a short sleeve having a clutch, c , secured 30 upon the axle b . This sleeve is preferably made in halves longitudinally, held together by the band c' and screws c'' , so that it may be applied to any axle without removing the car-wheels.

D is a long sleeve, which is mounted loose 35 upon the axle b . This sleeve is also preferably made in halves longitudinally, which halves are held together by the bands d and screws d' . One end of the sleeve D forms a clutch, d'' , which engages with the clutch c 40 when desired. A portion of the sleeve D forms a barrel, d'' , for the brake-chain to wind on. The opposite end of the sleeve is provided with the face-cam d^t , having the pocket d^s , the use of which will be more fully explained hereinafter, and d^s are collars on the sleeve for the end of the clutch-lever to bear 45 against.

E is the clutch-lever pivoted in the bracket e , which is secured to the center beam, a , of the frame. The lever E is provided with a forked end, e' , which engages between the col-

lars d^t , and e^2 is a spring secured to the car-frame, and to the opposite end of the lever E, for holding the clutches apart.

F is a hand-lever pivoted to the frame, and 55 connected to the brake-lever by the eyebolt f and link f' , so that it can be worked from the upper part of the car.

G is a hand-lever, which may be pivoted to any part of the side frame of the car, or to another car on the train, or to the engine. This lever G is connected to the lever F or to the lever E direct by means of the cord or chain g which passes over the pulley g' , pivoted in the bracket g'' on the car-frame. 65

H are the curved brake-blocks, provided with round stems h , which are carried by the plates h' h'' , secured to the brake-beams I. The plates h' are provided with eyes h^3 , which are pivoted on the hooks h^4 , projecting from the 70 car-frame. One brake-beam I is provided with a hook, i , connecting with one end of the brake-rod J, and the other brake-beam is provided with a bracket, i' , in which a lever, i'' , is pivoted. One end of the lever i'' connects with the other 75 end of the brake-rod J, and the other end of the lever is connected to the barrel d'' by means of the brake-chain K.

M is the clutch-disengaging block, which is securely bolted to the car-frame. N is a spring, 80 bolted to the block M, and carrying the latch-pin n on the end of it, which projects through the hole m in the said block.

The action of the brake mechanism is as follows: When the lever F or G is moved by 85 hand so as to move the lever E for a sufficient distance against the tension of the spring e^2 , the forked end of the lever E causes the sliding clutch to engage with the clutch c , which is secured on the axle. The rotary motion of 90 the axle is communicated to the barrel d'' , which winds up the brake-chain K, and the brake-beams, together with the brake-blocks, are drawn together by means of the rod J and lever i'' . When the barrel d'' has made nearly 95 a full revolution and the brakes are hard on, the spring latch-pin falls into the pocket d^s . This pocket is situated in the high part of the face of the cam d^t , which comes against the disengaging-block M as the cam revolves with 100 the axle. The pressure of the block M against the cam-face draws back the sleeve D and dis-

engages the clutches directly the latch-pin has fallen into the pocket, so that no more of the 5
brake-chain is wound upon the barrel, although the axles continue to revolve, and the
brake-blocks are held hard against the wheels
by the spring latch-pin. The brakes are relieved by simply letting go the hand-lever F
or G. The spring e^2 moves the lever E so that
the cam-face slides back clear of the latch-pin,
and the tension in the brake-chain and its
attachments moves the cam, so that the pocket
is clear of the pin, and the brake mechanism
is ready to be used again.

What I claim is—

- 15 1. In an automatic car-brake, the combination
of a clutch secured to the car-axle, a sleeve
sliding on the axle and provided with a clutch,
a winding-barrel for the brake-chain, and a
cam for disengaging the said clutches, a lever
20 for operating the sliding sleeve, and a disengaging-block for the said cam to bear against,
substantially as and for the purpose set forth.
- 25 2. In an automatic car-brake, the combination
of a clutch secured to the car-axle, a sleeve
sliding on the axle and provided with a clutch,
a winding-barrel for the brake-chain, and a
cam for disengaging the said clutches, having
the pocket d^3 in it, a lever for operating the
30 sliding sleeve, a disengaging-block for the said
cam to bear against, and a spring-latch secured
to the said block and engaging with the pocket
in the cam, substantially as and for the pur-
pose set forth.
- 35 3. In an automatic car-brake, the combination
of the revolute axle, a clutch secured to
the axle and made in halves longitudinally,
the band c' and screws connecting the halves
of the clutch, the sliding sleeve made in halves

longitudinally and provided with the clutch
 d^2 , the brake-chain barrel, and the cam d^4 ,
having pocket d^5 , the bands d , and screws d' ,
the disengaging-block M, the spring latch-pin,
and a lever for actuating the said sliding sleeve,
substantially as and for the purpose set forth.

4. In an automatic car-brake, the combination
of a revolute axle, a clutch secured to
the axle, the sliding sleeve provided with the
clutch d^2 , barrel d^3 , and cam d^4 , having pocket
 d^5 , the disengaging-block M, the spring latch-
pin, the clutch-lever E, provided with the
spring e^2 , a hand-lever connected to the clutch-
lever, the brake-beams provided with brake-
blocks and pivoted to the frame, the brake-
rod, the brake-chain, and the lever i^2 , pivoted
on one of the brake-beams, substantially as
and for the purpose set forth.

5. In an automatic car-brake, the combination
of the brake-beams provided with plates
 $h' h^2$, and pivoted to the car-frame, the brake-
blocks having stems h , the lever i^2 , pivoted on
one of the brake-beams, the brake-rod connect-
ing said lever with the other brake-beam,
the brake-chain K, the sliding sleeve provided
with clutch d^2 , barrel d^3 , and cam d^4 , having
pocket d^5 , the clutch secured to the axle, the
brake-lever E, provided with the spring e^2 ,
a hand-lever connected to the brake-lever, the
disengaging-block M, and the spring latch-pin,
substantially as and for the purpose set forth.

In testimony whereof I affix my signature in
presence of two witnesses.

WILLIAM F. CUMMINGS.
